UNITED STATES PATENT OFFICE.

CLARENCE W. VOGT, OF LOUISVILLE, KENTUCKY, ASSIGNOR TO VOGT BROTHERS MFG. CO., OF LOUISVILLE, KENTUCKY, A CORPORATION.

GRATE.

Application filed September 1, 1921. Serial No. 497,582.

This invention has to do with certain improvements in the construction of grates.

One object of the invention is to provide a construction which shall be very simple and which may be cheaply manufactured from castings with only a very small amount of finishing work being necessary.

The invention has to do with certain improvements in the construction of the grate bars themselves, as well as other improvements relating to the manner in which the grate bars are supported. In connection with the construction of the grate bars, one of the features of the invention relates to the provision of an improved type of sectional bar of such construction that it may be built in standard units which may easily be assembled, and which standard units will be interchangeable to the extent necessary 20 to standardize the parts.

In connection with the method of supporting the grate bars, I will state that one of the objects in this connection is to provide a construction such that the grate bars may be pivoted on centers practically flush with their top surfaces, so that when the bars are rocked, practically all of the movement will take place with respect to one edge or the other of the bars. Another object in this 30 connection is to provide a sectional and unit construction such that this pivoting of the bars close to their upper surfaces may be easily secured.

Other objects and uses of the invention 35 will appear from a detailed description of the same, which consists in the features of construction and combinations of parts hereinafter described and claimed.

Referring to the drawings:

Fig. 1 shows a longitudinal section through 40 the grate itself and also shows a portion of the operating mechanism by which the bars are rocked;

Fig. 2 shows a longitudinal section through 45 one of the grate bar units on enlarged scale, the central portion of the length of the unit being broken away in order to shorten the figure;

Fig. 3 shows a plan view of the grate bar 50 beam, the grate sections being removed, and the central portion of the beam being broken away in order to shorten the figure;

Fig. 4 shows a cross section taken on the line 4-4 of Fig. 3, looking in the direction 55 of the arrows;

Fig. 5 shows an end view of the beam of Fig. 3;

Fig. 6 shows a plan view of the end portions of two consecutive grate bar units on smaller scale; 60

Fig. 7 shows a side elevation of one of the grate bar sections;

Fig. 8 shows a plan view corresponding to Fig. 7;

Fig. 9 shows a cross section taken on the 65 line 9-9 of Fig. 7, looking in the direction of the arrows;

Fig. 10 shows an inside face view of one of the end grate bar sections;

Fig. 11 shows a plan view corresponding 70 to Fig. 10; and

Fig. 12 shows a back face view corresponding to Fig. 10.

Fig. 13 shows a plan sectional view of the stoker and grate mechanism, the rear portion of the grate being broken away in order to shorten the figure. 75

In Fig. 13 there is illustrated a hopper 20 of capacity sufficient to carry ordinarily at least as much fuel as would be stoked at a 80 given operation. Ordinarily, this hopper preferably will be of greater capacity than the amount just indicated. This stoker is intended to feed fuel through the opening 21 which leads into the combustion chamber, which fuel is supported by the grates. Ordinarily dead plate 28 extends across the front portion of the combustion chamber 85 between the side walls 29 and 30. A sectionalized fuel chute is set through the opening 21 and has its inner end 32 resting on plate 28. The chute transfers fuel from the front and bottom edge of the hopper to the grate bars which are located below and ahead of it. Slidable upon the hopper bottom plate 26 is a fuel feeding plate or ram 35 whose front end 36 is preferably slanted. Such front end also may be provided with a series of upstanding prongs or the like 37 which will assist in moving the fuel toward 90 and through the opening 21 without seriously impeding the withdrawal of the fuel plate 35 through the fuel remaining in the hopper. 95

The grate construction itself is best illustrated in Figs. 1 to 11 inclusive. It includes a series of units 49 of practically standard construction whose end portions are journaled in the side plates 50 and 51 which extend along the side portions 30 of the fur- 100 105 110

nace. These side plates 50 and 51 reach downwardly towards the back end of the furnace at an angle, so that the grate itself lies at an angle as shown in Fig. 1.

5 Each of the units 49 includes a grate bar beam 52 in conjunction with grate bar sections 53 and end sections 54. The grate bar beam 52 has a series of sidewise projecting ribs 55 which provide between them vertical channels or notches 56 oppositely disposed in pairs. Each of the grate bar sections is provided with a vertical upwardly extending notch 57 which is adapted to embrace the central portion of the grate bar beam 10 and seat between the flanges 55 and in the notches 56 and be thus held firmly in position. The upper portion of each grate bar section has a series of sidewise projecting bed forming teeth 58, so that the teeth of the 15 adjacent sections come close enough together in order to prevent the loss of fuel directly through the grate by forming a full supporting perforated grate bed.

The front portion of each grate bar section 20 has an arcuate skirt 59 formed substantially on the arc of a circle about which the grate bar unit is rocked. These skirts of the consecutive grate bar sections effectively co-operate to provide a practically 25 continuous arcuate closure along the front face of the unit. This will effectively prevent the entrance of clinkers or large chunks of material beneath the grate bar units or between adjacent rows of grate bar units, 30 and will also prevent unburned coal from dropping into the ash pit when the grate sections are rocked.

Each grate bar beam may be provided 35 with a longitudinal extending opening 60 in its central portion which opening greatly enhances the cooling effect, and will reduce warping of the beams by overheating. This is a very important point for the reason that if the beams should warp materially, 40 the units would be thrown out of line and might thus interfere with proper rocking.

In order to lock the grate bar sections 45 in place, they may be provided with side notches 61 adjacent to and herein shown communicating with the vertical notches 57 into which side notches may be inserted locking rods or pins 62 as clearly illustrated in Fig. 1.

The end portions of the grate bar units 50 are supported in rocking fashion with respect to the side bars 50 and 51. It is preferred that the pivotal supports for the grate bar units should be as close to their upper surface and as close to their rear 60 edges as possible. This will permit the grate bar units when rocked to rise over practically their entire surface, with a consequent backward movement, which will in itself greatly assist in transferring the fuel body 65 downwardly and over the grate towards its

back edge. At said back edge may be located a clinker plate 63 pivoted on the shaft 64 and normally held in raised position as shown in Fig. 1, but which may be dropped downwardly into the dotted line position of 70 said figure in order to discharge the clinkers.

In order to pivot the grate bar units in the manner above explained, and at the same time secure more strength and interchangeability in the parts, I have provided the end 75 units which are shown in detail in Figs. 10, 11 and 12. Each of these end units has an inside rectangular socket 65 which is adapted to receive the adjacent end 66 of the grate bar beam to which it may be locked by means 80 of a pin 67. Each of these end sections may be provided with side teeth 68 and with a front skirt 69, similar to those already discussed in reference to the grate bar sections. Each of these end sections is provided in its 85 upper rear corner with a sidewise projecting circular lug 70, which seats into a recess of the bar 50 or 51 as the case may be. By providing the end sections with these side lugs 70, it is possible to establish the pivotal 90 points out of line from the grate bar beam, and at the same time provide great strength in the parts.

I wish to also point out that by providing 95 a carrier bar 52 independent of the trunnion sections 54 the entire grate section need not be thrown away if an end section is burned out. Furthermore, the carrier bar 54 is at no point in direct contact with the fuel bed and the end or trunnion sections as well as 100 the intermediate grate sections are all replaceable at a fraction of the expense that would be incurred in replacing an entire unit.

One of the end sections of each grate bar 105 unit is provided with a downwardly extending arm 71 by means of which it may be rocked. These arms preferably extend rearwardly as shown in Figs. 1 and 10 when the grate bar units are in the normal position; 110 and by pulling the arms forwardly the grate bar units are tilted upwards. Ordinarily, the arms of the grate bar units may be coupled up in alternate groups as shown in Fig. 1. For this purpose, a bar 72 is provided 115 with lugs 73 which are pivoted to the arms 71 of the alternate units, and another bar similar to the bar 72 may be coupled up to the intermediate grate bar units. The rocking levers 75 and 76 are pivoted to the 120 front face of the furnace at the points 77 and 78; and said levers are connected to the bars 72 by means of the links 79 in the manner illustrated in Fig. 1.

The clinker plate 63 may be operated in 125 any suitable manner and I do not herein concern myself with the details thereof.

While I have herein shown and described only a certain embodiment of the features of my present invention, still I do not limit 130

myself to said embodiments except as I may so do in the claims.

I claim:

1. A readily detachable and renewable furnace grate including in combination a pair of spaced and inclined side supports having spaced bearings therein, a plurality of grate bar units each pivotally mounted in said bearings, adjacent units being rockable independently, each unit comprising a supporting beam, a plurality of independent intermediate notched sections straddling said beam and each including a substantially arcuate face extending upwardly and forwardly of the beam, and a pair of complementary independent end sections receiving the ends of said beam and each including a side-wardly projecting pivot positioned substantially in proximity to the upper and rear corner and seated in a side support bearing.

2. A device as defined by claim 1, wherein each exterior section is characterized by an arcuate face similar to the intermediate sections for completing the grate and maintaining a substantially closed grate for substantially the full width of the furnace.

3. A device as defined by claim 1, wherein the beam is characterized by a longitudinal aperture for securing substantially uniform expansion throughout.

4. A device as defined by claim 1 charac-

terized by each section being provided with a notch in the edge of its beam receiving portion, the beam being suitably formed adjacent said portion and notch to coact with the same, and a common locking member seated in said notches for securing all of the sections to the beam.

5. A device of the character described in claim 1 characterized by each grate section including a central plate terminating in an arcuate skirt, and a grate forming portion comprising laterally extending projections upon each of said plates, adjacent sections upon adjacent beams being positionable in close proximity to each other, whereby a substantially continuous but foraminated grate bed is secured which extends substantially the full length of the grate.

6. A device of the character described in claim 1 characterized by each grate section including a central plate terminating in an arcuate skirt, and a grate forming portion comprising laterally extending projections upon each of said plates, adjacent sections upon adjacent beams being always positionable in close proximity to each other whereby a substantially continuous but foraminated grate bed extends substantially the full length and width of the grate and at all times and for all positions of the grate sections.

CLARENCE W. VOGT.
